UNITED STATES PATENT OFFICE.

OSCAR LIEDTKE AND JOHN M. BIEN, OF NEWARK, NEW JERSEY.

SASH-LOCKING BAR.

1,308,287.

Specification of Letters Patent.

Patented July 1, 1919.

Application filed May 25, 1917. Serial No. 170,857.

To all whom it may concern:

Be it known that we, OSCAR LIEDTKE and JOHN M. BIEN, citizens of the United States, and residents of Newark, county of Essex, 5 and State of New Jersey, have invented certain new and useful Improvements in Sash-Locking Bars, of which the following is a specification.

This invention relates to sash locking bars 10 and has for its object to provide a simple, cheap and easily constructed locking bar adapted for use, for example, with a sash which may be bodily displaced from its ordinary position in the frame and rotated 15 to and held in any desired position.

Such windows may be used in a variety 20 of places and in any buildings or construction, but are more particularly adapted for use in rooms such as sleeping porches or sun parlors where it is desired to obtain a maximum of ventilation and in which it is desirable that the sash may be readily closed and held firmly and securely in its closed 25 position as well as in all adjusted positions.

Such window sashes are preferably displaceable outwardly from the building so 30 that they project therebeyond and when so projected can be rotated into any desired position. With a room, as, for example, a sun parlor, equipped with sashes of this character it readily becomes possible to project all the sashes outwardly and to turn them 35 into the position which, with the prevailing breeze, secures the best conditions of ventilation and circulation, and the sashes in such position can be firmly locked and held and can be changed into other positions and locked there with a minimum of exertion, and it is, of course, possible with the window 40 so constructed to readily obtain access thereto on both faces so that the same may be washed on both sides without personal inconvenience or danger. The entire window space can be made available with the sashes 45 completely open, and there is no sliding of sashes behind one another, or other cutting down of available openings.

In the drawing forming part of this specification and wherein the same reference numerals are uniformly used to designate the same parts throughout, Figure 1 is a perspective view of a sash in its frame, parts being broken away for the purpose of clear illustration and the sash being shown projected outwardly and placed substantially

parallel to its frame. Fig. 2 is a view in perspective of a locking means, and Fig. 3 is a transverse sectional view of the window shown in Fig. 1.

Reference character 10 is applied to designate what we have termed a sash, and which takes the place of the ordinary sash, and the window frame is shown at 11. Such frame is preferably cut away on the sill, as indicated at 12, though the cut away may be in the sash itself, and there is received in such cut away portion a link 13 pivoted in the frame at 14 and pivoted in the sash at 15, and at the upper end there is a similar link 13' pivoted in the frame at 14' and in the sash at 15'. The locking means comprises a notched bar 16, the notches 17 being placed preferably opposite one another, and the same is secured to the sash by means of a bracket 18 and the bar 16 is preferably provided near the bracket 18 with a hinge joint 19. On the window sill is a notched plate 20, the notches thereof being of a size to receive the portions 21 of the bar 16 between the notches 17 and to hold the same in a manner which will be readily understood. The locking member 20 is preferably arcuate in form and is preferably arranged on the sill in substantially the manner shown, the end 22 thereof being farther to the front of the frame than the opposite end 23 so as to form substantially a quadrant of a circle with one end directed outward.

The operation of the device will be readily understood from the foregoing. The sash, when closed, rests against the stops 24 in the frame, the members 13 and 13' being received in slots provided therefor, either in the sash or in its frame, as may be considered preferable. When the sash is pushed outwardly it is supported by the links 13 and 13' and may be turned on the pivots 15, 15' to any desired position, and when so turned may be locked by inserting the bar 16 in the desired notch in the plate 20, which serves to hold the member 16 both against inward and outward movement and also against rotation, the part 21 of the bar 16 fitting closely in the notches in the arcuate member 20. When it is desired to change the adjustment of the sash or to swing it to a different position, the bar 16 may be lifted, this being permitted by the provision of the hinged joint 19, the sash turned and moved into the desired position and the bar

16 replaced in co-action with the plate 20 and in the proper position to bring about the proper adjustment.

It is to be understood that while we have 5 illustrated the preferred embodiment of our invention, that nevertheless the same is to serve only for the purpose of affording a clear understanding of our invention and that we are not limited to the specific features thereof, save as is required by our 10 claims, and that changes and modifications in the particular form shown and described may be resorted to within the scope of our claims and without departing from or sacrificing the advantages of our invention. 15

Having thus described our invention, what we claim is:

1. A notched locking bar for a movable sash pivotally secured to the sash at the 20 lower end thereof and having a hinge joint between its ends, and an arcuate notched member adapted to be secured to the window sill and to receive notched portions of said bar and thereby hold and lock the sash

in position, said arcuate locking member 25 being placed with one end directed substantially longitudinally of the window sill and the other end directed outwardly.

2. A locking bar for a movable sash, said bar being pivotally secured to the sash at 30 the lower end thereof and provided with a hinge joint near its pivotal mounting, and said bar having opposite substantially vertical notches in its sides, and an arcuate member 35 having notches in its upper surface and adapted to be placed on the window sill and to receive the notched portions of said bar in its notches and thereby hold and lock the sash in position, said arcuate member being placed with one end directed substantially 40 longitudinally of the window sill and the other end directed outwardly.

In testimony that we claim the foregoing, we hereto set our hands, this 24th day of May, 1917.

OSCAR LIEDTKE.
JOHN M. BIEN.
